US00D955382S

(12) **United States Design Patent** (10) **Patent No.:** **US D955,382 S**
(45) **Date of Patent:** **** Jun. 21, 2022**

(54) **STORAGE DEVICE**

(71) Applicant: **HANWHA TECHWIN CO., LTD.**,
Seongnam-si (KR)

(72) Inventors: **Ho Jin Park**, Seongnam-si (KR); **Mun Jun Park**, Seongnam-si (KR)

(73) Assignee: **HANWHA TECHWIN CO., LTD.**,
Seongnam-si (KR)

(**) Term: **15 Years**

(21) Appl. No.: **29/741,112**

(22) Filed: **Jul. 9, 2020**

(30) **Foreign Application Priority Data**

Jan. 14, 2020 (KR) 30-2020-0001723

(57) **CLAIM**

The ornamental design for a storage device, as shown and described.

DESCRIPTION

FIG. 1 is a perspective view of a storage device, showing the new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is another perspective view thereof where portions of the storage device are shown separate and enlarged, for clarity of illustration.

The evenly spaced broken lines depict portions of the storage device and form no part of the claimed design.

The uneven broken lines are included to indicate portions of the figures shown enlarged and form no part of the claimed design.

1 Claim, 8 Drawing Sheets
